DESIGN FOR A STOCKING

Roy E. Tilles, New Rochelle, N. Y.

Application September 25, 1942, Serial No. 108,334

Term of patent 3½ years

To all whom it may concern:

Be it known that I, Roy E. Tilles, a citizen of the United States, residing in New Rochelle, county of Westchester, State of New York, have invented a new, original, and ornamental Design for a Stocking, of which the following is a specification, reference being had to the accompanying drawing, forming part thereof.

In the drawing:

Fig. 1 is a side elevational view of a stocking showing my new design; and

Fig. 2 is a fragmentary rear elevational view thereof on a larger scale.

I claim:

The ornamental design for a stocking, as shown.

ROY E. TILLES.
